G. G. GILPIN

DUMP CAR

Filed Nov. 26, 1919

Garth G. Gilpin Inventor
Barney Gilligan Attorney

UNITED STATES PATENT OFFICE.

GARTH G. GILPIN, OF RIVERSIDE, ILLINOIS, ASSIGNOR TO WALTER P. MURPHY, OF NEW YORK, N. Y.

DUMP CAR.

Application filed November 26, 1919. Serial No. 340,907.

To all whom it may concern:

Be it known that I, GARTH G. GILPIN, a citizen of the United States, residing at Riverside, in the county of Cook and State 5 of Illinois, have invented certain new and useful Improvements in Dump Cars, of which the following is a specification.

My invention relates to dump cars and particularly to the doors or hinged bottom 10 panels in cars of this type. It has for its principal object the provision of a door of this type made of cast metal, preferably cast steel or malleable iron. Bottom doors for dump cars must be very strong and rigid so 15 that they will not sag under load or become bent or warped under the stresses to which they are subjected. A cast metal door made in accordance with the principles of my invention possesses the foregoing characteris- 20 tics and has the desirable advantage of being cheaper than doors made of rolled or wrought material, and without being of prohibitive weight.

A further object is the construction of a 25 cast door which will not warp in cooling after the casting thereof or during the annealing process. Any warping of the hinged bottom doors or panels is likely to interfere with the proper manipulation of 30 the dumping mechanism of the car besides making the car leaky.

The invention consists in the novel and improved constructions and arrangements to be hereinafter described and claimed, for 35 carrying out the above stated objects and such other incidental objects as will be hereinafter described.

A preferred embodiment of my invention is illustrated in the drawing wherein;

Fig. 1 is a fragmentary plan view of a 40 dump car provided with hinged bottom doors embodying my invention.

Fig. 2 is a transverse section of my im- 45 proved panel taken at right angles to the hinge.

Fig. 3 is a perspective thereof illustrating the construction of the lower side of the panel or door.

Like characters of reference designate like 50 parts in the several figures of the drawings.

My improved panel or door 10 is applica- 105 ble to dump cars of different design and construction, which constructions are well known and need not be described in detail.

herein. For purpose of illustration I have 55 shown in Fig. 1 a portion of a dump car of steel construction having side walls 11 and end wall 12 having top edge flanges 13 and 14 respectively. The top chord of the body bolster 15 and the inwardly extending 60 flanges 16 and 17 running along the sides and end of the car form a door framing for the bottom door or panel. The doors are hinged at 18 along the center line of the car to the center sill. The hinge is covered with 65 a strip 19 extending from the flange 17 to the top chord of the body bolster and thus completes the framing for the bottom panel. This also prevents leakage of material from 70 the car at the hinges.

In Figs. 2 and 3, I have shown my cast 75 metal panel or door which may be formed of cast steel or malleable iron depending on the conditions under which the door is used. My invention, however, is not limited to the 80 exact material used and out of which the door is cast. The marginal flanges 20, 21, 22 and 23, the transverse reinforcing rib 24, the hinge members 25 and the angular reinforcing ribs 26 are all cast integral with the 85 body 27 of the door 10. Certain of the angular reinforcing ribs 26 are preferably placed opposite the hinges 25 so as to reinforce the panel at this point. The body 27 of the panel is preferably corrugated or otherwise 90 embossed at 28, such corrugations or the like being cast integral with the panel. The bosses or corrugations in the body of the panel reinforce the same under the load of the contents of the car and also prevent the 95 warping of the panel out of a plane while the same is cooling after being cast or during the annealing process. As stated above it is absolutely essential that the margins 29 of the panel lie in a plane so as to prevent 100 leakage from the car and also so as not to interfere with the manipulation of the dumping mechanism. The marginal flanges and the transverse reinforcing ribs also assist not only in strengthening the panel un- 105 der load but in preventing the warping of the panel while cooling or during annealing.

As many transverse reinforcing ribs 24 may be provided as is necessary to properly strengthen the panel. The panel is prefer- 105 ably corrugated transversely as shown, though the direction of the corrugations and their shape is immaterial. In case the tend-

ency to warp is excessive, the corrugations may be cast in the panel running in both directions.

Suitable mechanism of any well known type is provided for operating the door and for holding the same closed against a load. However, such mechanism forms no part of this invention and accordingly is not illustrated or described.

10 I claim:

1. A hinged door for a railway dump car, comprising a cast metal panel formed without turned rigidifying flanges cast integrally therewith, hinge elements cast to said flanges and corrugations cast therein which terminates within the panel.

2. A hinged door for a railway dump car, comprising a cast metal panel formed without turned rigidifying flanges at its edges cast integral therewith, hinge elements cast to said flanges, angular reinforcing elements cast in the angle between said panel and said flanges for reinforcing the same at the hinges and corrugations cast in said panel for rigidifying the same against deflection when in use and against warping while cooling.

3. In a railway dump car, the combination with the body of the car, of a hinged door forming part of the bottom of the car and adapted to assume an inclined position for dumping, comprising a cast metal panel having marginal flanges and corrugations cast integral therewith, and also a reinforcing rib transverse to said corrugations and cast integral with said panel and flanges, all for reinforcing said panel and for preventing the warping of same while cooling after being cast, hinge members cast integral with said flanges and reinforcing fillets cast in the angle between panel and flanges and opposite the hinges for reinforcing the same.

4. In a railway dump car, the combination with the body of the car, of a hinged door forming part of the bottom of the car and adapted to assume an inclined position for dumping, comprising a cast metal panel having marginal flanges and corrugations cast integral therewith, and also a reinforcing rib transverse to said corrugations and cast integral with said panel and flanges, all for reinforcing said panel and for preventing the warping of same while cooling after being cast, hinge members cast integral with said flanges and reinforcing webs cast in the angle between said panel and said flanges for further rigidifying said door.

5. In a railway dump car, the combination with the body of the car, of a hinged door forming part of the bottom of the car and adapted to assume an inclined position for dumping, comprising a cast metal panel having means cast integral therewith for rigidifying the same and for preventing the warping thereof while cooling after being cast comprising corrugations in said panel, marginal flanges extending at an angle thereto, a reinforcing rib transverse to said corrugations and cast integral with said corrugations and said flanges and reinforcing webs cast in the angle between said flanges and said panel.

6. A door structure of the character described comprising a cast metal plate provided with body and marginal reinforcements adapted to resist the tendency of the plate to be distorted by the stresses incident to the unequal cooling of the casting; said reinforcements comprising rigidifying marginal ribs, corrugations extending across the plate, and terminating within the edges of the plate, and a rib extending across said corrugations.

GARTH G. GILPIN.
